SIGNAL

Wilbur A. Heidel, Minneapolis, Minn.

Application January 5, 1940, Serial No. 312,560

10 Claims. (Cl. 177—329)

This invention relates to a signal which can be employed for a variety of purposes, but which has been designed to be more especially used as an automotive vehicle signal.

This application is a substitute for and substantial duplicate of applicant's application S. N. 590,124, filed February 1, 1932, and allowed May 28, 1936, which application is now abandoned.

An object of the invention is to provide a signal consisting of means, such as a lamp, from which rays of light can emanate, a housing or casing for said means or lamp having an open side, which will desirably be closed by a transparent or translucent cover such as glass, shutter means between the lighting means or lamp and open side for arresting the travel of light from said lighting means or lamp through or past the open side of said housing or casing and means for actuating said shutter means to cause rays of light emanating from the lighting means or lamp to intermittently emanate from the open side of said housing or casing, whereby to provide intermittent flashes of light for producing a warning signal.

A further object is to provide an automotive vehicle stop light signal consisting of means, such as a lamp, from which rays of light can emanate, a housing or casing for said means or lamp having an open side, a pair of rotatable shutters or disks arranged adjacent each other and between the lighting means or lamp and open side for arresting the travel of light from said lighting means or lamp through or past the open side of said housing or casing, each of said shutters or disks having spaced apart openings therethrough, and means for revolving said shutters or disks in opposite directions to cause openings in the different shutters or disks to align and rays of light emanating from said lighting means or lamps to pass through said aligning openings as said shutters or disks revolve and to thus intermittently emanate from the open side of said housing or casing, whereby to provide intermittent flashes of light for producing a warning signal.

A further object is to provide a signal as stated, wherein a plurality of spaced apart openings in a shutter or disk of the signal will each be provided with a colored, translucent covering member and the covering member over one of said shutter or disk openings will have color different from that of the covering member over another of said shutter or disk openings, whereby the intermittent flashes of light provided can be any single color or any plurality of different colors flashed in a preferred sequence to produce a desired effect.

A further object is to provide a signal as stated, wherein the means for actuating or revolving the shutter means or disks will be an ordinary type of electric motor.

A still further object is to provide a signal as stated, wherein will be incorporated improved features and characteristics of construction novel both as individual entities of the signal and in combination with each other.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible so long as within the spirit of the invention and the scope of the claims which follow.

In the accompanying drawing forming a part of this specification,

20 Fig. 1 is a fragmentary sectional view of a signal made according to the invention;

Fig. 2 is a sectional view, partially in elevation and on a reduced scale, of the whole of the signal which is disclosed in Fig. 1;

25 Fig. 3 is an elevational view of the signal as seen from the front thereof;

Fig. 4 is a transverse sectional view taken as on line 4—4 in Fig. 2; and

30 Fig. 5 is a transverse sectional view taken as on line 5—5 in Fig. 2.

With respect to the drawing and numerals of reference thereon, 10 denotes a desirable metallic casing housing a bulb or lamp 11 therein, said lamp being mounted in the casing as denoted generally at 12. The casing 10 includes an open side 13 which is covered by an ordinary lens or pane 14 of transparent or translucent glass or other suitable material. The lens or pane 14 is mounted in the casing as denoted generally at 15.

40 As disclosed, the casing 10 with lamp or bulb 11 and transparent or translucent cover 14 constitutes an automotive vehicle stop light or signal adapted to be supported upon the rear of an automotive vehicle, as at 16, but it is to be understood that the present signal can be employed as a warning signal generally and need not necessarily be employed upon an automotive vehicle.

45 The inner, parabolic surface 17 of the casing 10 is constructed to serve as a reflector for the lamp 11.

50 A pair of rotatable shutters or disks, represented 18 and 19 respectively, are arranged adjacent each other and between the lighting means or lamp 11 and the open side of the casing to arrest the travel of light from said lighting means or lamp through or past the open side 13 of the casing 10 and each of the shutters or disks 18 and 19 has spaced apart openings, indicated 55 20 and 21 respectively, therethrough. As disclosed, each shutter or disk has four openings of

sector-shape which are spaced equidistantly about the shutter or disk. The pane 14 is solid glass which completely covers the open side 13 of the casing 10.

The disks 18 and 19 are adapted to be revolved in opposite directions to cause the openings 20 and 21 in the different shutters or disks to aline to thus allow rays of light emanating from the lighting means or lamp to pass through alining openings as the shutters or disks revolve, whereby said rays of light will intermittently emanate from the open side of the housing or casing and through the pane 14 to provide intermittent flashes of light for producing a warning signal.

A stationary axle or shaft for the shutters or disks 18 and 19 is denoted at 22. Said shaft 22 is supported at its outer end upon the pane 14 and at its inner end fixedly carries a member 23 which provides the field, of the permanent magnet type, of an ordinary electric motor for actuating the shutters or disks 18 and 19.

As disclosed, the outer end of the stationary shaft 22 has a reduced threaded extension 24 which passes through a threaded opening in an externally threaded fitting 25. A thumb nut 26 upon the threaded extension 24 and turned down against the fitting 25 rigidly fastens the axle or shaft 22 to said fitting. The fitting 25 freely passes through an opening 26a arranged centrally of the pane 14 and is held in stationary relation to said pane by means of annular, internally threaded washers 27 which are screwed on member 25 and engage the inner and outer surfaces of the pane 14. The member 23 providing the field of the electric motor has a central threaded opening 28 arranged upon an inner reduced threaded extension 29 of the axle or shaft 22 and a thumb nut 30 upon said threaded extension 29 and turned down against the member 23 rigidly fastens said member to the axle 40 or shaft 22.

The shutters or disks 18 and 19 may be of any preferred material suitable to their purpose. Said shutters or disks are spaced apart slightly and are mounted upon the stationary axle or shaft 22 to be perpendicular thereto and parallel with the pane 14. As disclosed, the shutter or disk 18 includes a hub 31 which is perpendicular to the body of the shutter or disk and extends inwardly therefrom, said hub 31 being rotatably mounted upon the axle or shaft 22 between the member 23 and an inner shoulder 32 upon said axle or shaft. The shutter or disk 19 includes a hub 33 which is perpendicular to the body of the shutter or disk and extends outwardly therefrom, said hub 33 being rotatably mounted upon the axle or shaft 22 between the fitting 25 and an outer shoulder 34 upon said axle or shaft.

The member or field 23 includes an annular flange 35 which concentrically surrounds the hub 31 in spaced relation thereto, and the externally threaded portion of the fitting 25 which is carried by the annular threaded members 27 is in spaced relation to the hub 33 as will be more clear from Fig. 1.

The stationary axle or shaft 22 can be carried solely by the pane 14 as disclosed and in turn stationarily carry the member 23 or an additional support (not shown) for said member 23 can be provided.

The electric motor including the field 23 may also include an ordinary type of armature 36 with insulated windings 37, commutator 38 and brushes 39, ordinary lead wires to said brushes

being designated 40 and 41. The armature is a three-pole armature and the commutator is a three-segment commutator, although the structure can be varied in this regard. The armature 36 and the commutator 38 are fixed to rotate with the hub 31 but separated therefrom by insulation 42 and said armature and commutator are themselves separated by insulation 43. The brushes 39 are insulatedly mounted in the member 23, as at 44, to engage the commutator in ordinary fashion and the armature is surrounded by the annular flange 35 of said member 23.

The lead wires 40 and 41 extend from a source of electric current supply which may be the same source as that for lighting the lamp 11. When the electric circuit including said lead wires 40 and 41 is closed, the electric motor will, obviously, be energized and the armature 36 will thus be caused to rotate to in turn rotate the hub 31 and with it the shutter or disk 18, upon the stationary axle or shaft 22.

An annular L-shape web 45, which connects the body of the shutter or disk 18 with the hub 31, is constructed to provide a bevel gear 46 which meshes with a pinion 47 fixed upon a pin 48 carried by the stationary axle or shaft 22. An annular L-shape web 49, which connects the body of the shutter or disk 19 with the hub 33, is constructed to provide a bevel gear 50 with which the pinion 47 meshes. The L-shape web 45 is disposed inwardly from the body of the shutter or disk 18 and the L-shape web 49 is disposed outwardly from the body of the shutter or disk 19 to space the bevel gears 46 and 50 apart in order that these may properly engage the pinion 47. The shoulders 32 and 34 cooperate with the member 23 and the hub 31 and the fitting 25 and the hub 33, respectively, to maintain the bevel gear and the pinion in the desired relation as will be understood.

It will be evident that upon rotation of the shutter or disk 18 by energization of the electric motor in the manner as set forth, to revolve the shutter or disk 18, the hub 31 and the bevel gear 46, said bevel gear 46 will act upon the pinion 47 to cause this to be revolved and said pinion will in turn act upon the bevel gear 50 to revolve the shutter or disk 19 and the hub 33 in direction opposite that in which said shutter or disk 18 is being revolved.

The openings 20 and 21 in the shutters or disks 18 and 19, respectively, are arranged relatively to each other so that upon rotation of said shutters or disks in opposite directions, the openings in the different shutters or disks will successively aline, as will be apparent and allow rays of light emanating from the lighting means or lamp 11 to pass through the alining openings as the shutters or disks relatively revolve to thus intermittently emanate from the open side of the casing 10, through the transparent or translucent pane 14 as shown, whereby to provide intermittent flashes of light for producing a warning signal.

As shown, each of the spaced apart openings 20 in the inner shutter or disk 18 is provided with a colored, translucent covering member, represented 51, said covering members 51 desirably being of Celluloid and attached against the inner surface of the shutter or disk 18 by means of rivets 52. Each of the covering members 51 may be a different color, or all of said covering members may be the same color, or one or a plurality may be the same color while

others are of variant color. It has been found that a very effective result is produced by providing each of the four openings 20 with a covering member having color different from the colors of all of the other covering members for said openings, as, for example, one red, one green, one yellow and one blue.

In Fig. 5 the arrows indicate that the shutters or disks 18 and 19 are travelling in opposite directions. The rays of light shine through the openings in both shutters or disks and through the colored covering members when said shutter or disk openings totally or partially align. The shutters or disks 18 and 19 are of course composed of opaque material, metal or fibre, for instance, and the effect of relative rotation of the shutters or disks in the arrangement as disclosed is the production of eight flashes of four different colors in four different positions for each complete revolution of the shutters or disks. Other effects too innumerable to be mentioned can evidently be produced, as, for example, an optical effect of rotation, the dead portions travelling one way and the colors travelling the opposite way, etc.

In cases where all of the covering members 51 are the same color, the intermittent flashes of light will also be a single color. By the employment of covering members 51 having several different colors, a plurality of different colors can be flashed through the pane 14 to produce any desired and predetermined effect.

It will be apparent that by varying the color scheme of the covering members 51, warning signals of a variety of different colors and combinations of colors can be produced. Also, the signalling effect can be varied by altering the relative rates of speed of rotation of the shutters or disks 18 and 19. As disclosed, said shutters or disks travel at equal speed in opposite directions. Obviously, the arrangement could be such that the shutters or disks will rotate at unequal rates of speed either in opposite direction or in the same direction.

In practice, when the signal is employed as an automotive vehicle stop light signal, it may be that the lamp 11 is normally dark, but becomes energized, together with the electric motor of the signal, when the vehicle operator depresses his brake lever to close an electric circuit, or circuits, including the lamp 11, as well as the lead wires 40 and 41. Immediately upon energization of the electric motor, the shutters or disks 18 and 19 commence to revolve and upon de-energization of said electric motor, said shutters or disks immediately come to rest.

It will, of course, be understood that various changes may be made in the form, details, arrangement and proportions of the parts, without departing from the scope of applicant's invention, which generally stated, consists in a device capable of carrying out the objects above set forth, in the parts combinations of parts disclosed and defined in the appended claims.

What is claimed is:

1. A signal device having in combination, a housing having an open front side and being substantially circular in vertical cross section, a lens covering said open side, a lamp disposed axially of said housing in its rear portion, shutter means between said lamp and said lens for intermittently arresting the travel of light from said lamp through said lens and means between said lamp and lens supported by said lens and spaced from said housing for rotating said shutter means to 75

cause flashes of light to pass from said lamp through said lens to produce a warning signal.

2. A signal device having in combination, a housing having an open front side, a lens carried by said housing enclosing said side, a lamp mounted in the rear portion of said housing, a pair of oppositely rotating shutter members each having openings therethrough between said lamp and said open side, actuating means for rotating said shutter members in opposite directions to interrupt the light from said lamp and cause flashes of light to pass through said lens, and means carried by said lens for supporting said shutter members and actuating means, said shutter members and actuating means being spaced from said housing.

3. A signal device having in combination, a housing having an open front side, a transparent cover for said side, a lamp disposed centrally of said housing and about the same horizontal axis as said housing, rotatable shutter members having openings therethrough between said lamp and cover and an electric motor between said lamp and cover having an armature shaft coaxial with said lamp and shutter members for rotating said shutter members in opposite directions to cause flashes of light to pass from said lamp through said cover, said motor being spaced from said housing.

4. A signal device having in combination, a housing having a cylindrical front portion and having an open front side, a transparent or translucent cover closing said side, a lamp mounted in said housing, rotatable shutter members between said lamp and said cover and spaced from the wall of said housing, and means spaced from said housing for rotating said shutter members, said lamp, shutter members in opposite directions and last mentioned means being coaxial with said housing, said shutter members acting to cause intermittent flashes of light to be transmitted through said cover.

5. A signal device having in combination, a housing having an open front side, a transparent cover for said open side, a lamp disposed in the rear portion of said housing, a member supported by and centrally of said cover, a shaft secured in said member, a pair of rotatable disks mounted on said shaft in front of said lamp for rotation thereon, said disks forming shutters and having circumferentially spaced openings therein disposed between said shaft and the edges of said disks, said openings in one disk registering with the openings in said other disk, a motor mounted on said shaft, and means driven by said motor for revolving said disks in opposite directions, whereby intermittent flashes are transmitted from said lamp through said cover, said lamp and shaft being arranged coaxially with said housing.

6. A signal device having in combination, a housing having a central horizontal axis, a lamp mounted in the rear of said housing coaxially therewith, said housing having an open front side, a transparent cover for said side, a member mounted in said cover coaxially with said housing, disk members journaled on said member for rotation about the axis thereof and between said lamp and cover, an actuating means for rotating said disks in opposite directions carried by and rotatable about the axis of said member and spaced from said housing, said disks respectively having circumferentially spaced openings therethrough which register in the rotation of said

disks whereby flashes of light are intermittently transmitted through said cover.

7. A signal device having in combination, a housing formed about a horizontal central axis, a lamp mounted in said housing, said housing having an open front side, a transparent cover closing said side, a shaft carried by said cover and projecting rearwardly into said housing, a pair of disks each having a portion journaled on said shaft for rotation thereon and disposed between said lamp and cover, a motor mounted on said shaft spaced from said housing and having a rotatable portion secured to one of said disks, said disks having adjacent portions formed as gears and a pinion carried by said shaft between and meshing with said gears, whereby both disks are driven in opposite directions by said motor, said disks having respectively circumferentially spaced openings adapted to register, said disks thus forming shutters whereby flashes of light are transmitted through said cover, said lamp and shaft being arranged coaxially with said housing.

8. A signal device having in combination, a housing having a central axis and an open front end, a lens closing said front end, a lamp mounted in the rear of said housing and coaxial therewith, a bearing supported by and centrally of said lens, a shaft carried in said bearing coaxial with said housing and projecting rearwardly thereinto, a pair of disks each having a portion journaled on said shaft for rotation thereon, a motor mounted on said shaft and having a rotatable portion connected to one of said disks and gearing between

5 said disks whereby both disks are driven by said motor in opposite directions, said disks each having circumferentially spaced openings therethrough between said shaft and the edges of said disks, said openings registering in the respective disks, said disks thus forming shutters whereby flashes of light are transmitted through said lens.

10 9. A signal device having in combination, a housing having an open front side, a lens closing said front side, a lamp mounted in said housing, a member mounted and carried in said lens, rotatable disks between said lamp and lens mounted on said member, said disks having openings therethrough between said member and their edges, said openings in one disk registering with those in another and an actuating means mounted on said member independently of said housing for rotating said disks in opposite directions so as to cause registration of said opening at very small intervals.

15 20 10. A signal device having in combination, a housing having an open front side, a lens closing said side, a lamp in the rear of said housing, a member supported by said lens in front of said lamp, rotatable disks mounted on said member having circumferentially spaced openings therein between said member and their edges, the openings in one disk registering with those in another and an actuating means for said disks also mounted on said member and disposed in front of said lamp for rotating said disks in opposite directions, said rotating disks causing flashes of light to be transmitted through said lens.

WILBUR A. HEIDEL.
